(57) **CLAIM**

The ornamental design for a scribe strip holder, as shown and described.

DESCRIPTION

FIG. 1 is an isometric view of a scribe strip holder showing my new design, with clamping screws shown in dashed lines not being part of the design;

FIG. 2 is an isometric view of the scribe strip holder without the clamping screws; The holes shown in dashed lines are not part of the design;

FIG. 3 is a top plan view thereof;

FIG. 4 is a front elevational view thereof, the rear being a mirror image of the front;

FIG. 5 is a right side elevational view thereof;

FIG. 6 is a bottom plan view thereof; and,

FIG. 7 is a left side elevational view thereof.
